UNITED STATES PATENT OFFICE.

ALFRED STELL, OF STEETON, NEAR KEIGHLEY, AND JOHN STELL, OF KEIGHLEY,
ENGLAND.

DOFFING APPARATUS FOR SPINNING AND LIKE MACHINES.

1,263,715.

Specification of Letters Patent. Patented Apr. 23, 1918.

Application filed November 26, 1915. Serial No. 63,426.

To all whom it may concern:

Be it known that we, ALFRED STELL and JOHN STELL, subjects of the King of Great Britain, and residents, respectively, of Greenhill, Steeton, near Keighley, in the county of York, England, and 30 Devonshire street, Keighley aforesaid, have invented a certain new and useful Improvement in Doffing Apparatus for Spinning and like Machines, of which the following description, together with the accompanying sheets of drawings, is a specification.

Our invention relates to improvements in doffing apparatus for spinning, twisting, doubling and like machines used in the production of yarns or threads of fibrous substances, particularly of the type known as "flier spinning" machines, and wherein the spindles are supported in bearings at their upper ends. Our present invention consists in the application of improved devices to doffing apparatus of this description for the purpose of holding upon and releasing the full bobbins from their spindles, the same device being also employed for supporting and moving the empty bobbins and for guiding or moving the yarns or threads to the desired sides of the spindles at the time and in the manner hereinafter described. These devices are carried by the parts which operate or move the rail supporting the spindles, by which means they are at all times simultaneously moved, although portions thereof are separately movable relatively to the spindles in the manner and for the purposes hereinafter described.

In the accompanying sheets of drawings:—

Figure 1 is a sectional end elevation of a sufficient portion of a machine for spinning, flax, hemp, jute, or the like, to show the application of our invention thereto, the spindles being shown in the spinning position.

Fig. 2 is a similar view to Fig. 1, but illustrates the spindles as though canted or moved at an angle to the vertical plane.

Fig. 3 is a front elevation of a portion of said spinning machine the spindles being shown in dotted lines in order that our improved parts may be more clearly seen.

Our improvements are equally applicable to machines for spinning or treating woolen or worsted yarns, or flax, jute or other similar yarns or threads.

In the accompanying sheets of drawings

A represents the spindles upon which the fliers 1 are mounted, these being supported at their upper ends by the rail 2, and are driven by whirls 3. The plate 2 is movable upon its fulcrum 4 which is supported by brackets 5 from the rail 6 which extends across the machine. The spindles A are steadied at their lower ends by bearings 7 in the spindle rail 8. Racks 9 and pinions 10 operated from the shaft 11 raise and lower said rail 8, the shaft 11 being oscillated by an appropriate handle of well known type mounted at the end of the machine, the oscillations of the rail 2 being also effected by another handle mounted at the end of the machine. The lifter plate 12 is traversed in any well known manner as by the rod 13, chain 14, chain pulleys 15, and shaft 16, these being automatically rotated from the building motion of the machine in order that the bobbins B may be reciprocated at the desired rate of speed between the lower ends of the fliers 1 to regulate the winding of the yarns on the bobbins B in their proper positions thereto. Means are also employed for rotating the shaft 16 by hand for the purpose of manually raising and lowering the lifter plate 12 as and whenever desired. The cross bar 17 is employed as a guide for the racks 9 and other parts, as will be readily understood. In the case of machines for spinning flax and the like, tension is applied to the bobbins B by the bands 51 and weights 52 the former resting against the surfaces of grooves formed in said bobbins, and means of any desired construction are employed for simultaneously applying and removing said tension bands.

In carrying our invention into effect we mount quadrants 18 upon the cross rail 2 and these quadrants 18 gear with other quadrants 19 fixed at desired intervals upon the shaft 20 any suitable means, such as the well known quadrant lever (not shown) being employed to hold said shaft, so that it definitely occupies two positions, one when the spindles are in their vertical positions, as shown by Fig. 1, and the other when they are in their inclined positions as shown by Fig. 2. The operative may then know that by said lever resting within one notch or the other the spindles are in one of their two correct positions, namely, the vertical position, and that in which they are moved

to liberate the full bobbins and have empty ones substituted therefor.

Mounted in brackets 21 on the quadrants 18, is a rod 22 having fixed upon it the usual series of devices 23 for steadyng the spindles A, this shaft 22 being oscillated by a handle arranged at the end of the machine for the purpose of moving said steadyng arms into or out of contact with the spindles 10 A the two positions being indicated in full and broken lines in Fig. 2. Also fixed upon the quadrants 18 are bearings 24, through which takes a shaft 24^a having pinions 25 mounted thereon, the said shaft being rotated by a handle or hand wheel mounted at or near its end. The pinions 25 gear with racks in order that these latter may be thereby traversed through the bearings 24 in a direction approximately parallel with 15 the spindles A. Mounted on the racks 26 are bearings 27 having a shaft passing therethrough, said shaft being provided with a handle at the end of the machine by which it may be turned or rotated. This shaft 28 20 carries pinions 29 gearing with racks 30 which latter slide through the bearings 27 and carry at their outer end the shaft 30^a which is capable of being oscillated by a suitable handle. The shaft 30^a is provided 25 with a series of plates 31 mounted thereon in positions opposite or approximately opposite to the spindles A, and these plates have one, two or more projecting pins 32, which are for the purpose of entering the yarns 30 on the full bobbins when same are in their 35 positions upon the spindles A either when said spindles are vertical or at an angle to the vertical plane. The oscillation of the shaft 30^a draws such pins away from the bobbins whereby they may be released to 40 fall upon their pegs in manner hereinafter described, while by advancing the racks 30 and lowering the racks 26 into an appropriate position said pins 32 may be employed to lay hold of the threads extending 45 from the full bobbins to the fliers and move them to the requisite sides of the spindles and after lowering said racks slightly farther and again oscillating the shaft 30^a the 50 pins 32 may be passed beneath the flanges of the empty bobbins 33, when by raising the racks 26 said empty bobbins 33 are also raised on their spindles and held there until the latter are returned to their vertical positions 55 after doffing operations have been performed, the pins being withdrawn by withdrawing the racks 26 within their bearings 27.

We preferably employ two series of pegs 60 34, 35, which may be mounted upon one rail or upon two rails 36, 37, as shown by the drawings, said rails being supported by a series of racks 38 which engage with pinions 39 fixed upon the shaft 40. Said shaft 65 40 is supported by appropriate bearings 41

suitable means (not shown) being employed to limit movement of said shaft, so that the series of pegs 34, 35, may be moved from the position they occupy in Fig. 1, to the position they occupy in Fig. 2, the former 70 being that wherein the pegs 34 receive the series of full bobbins B, and in Fig. 2 that in which the full bobbins have been moved away and the spindles A are in position for receiving the series of empty bobbins 33 as 75 they are raised upon said spindles from their pegs 35. In both cases one of the series of pegs is in alinement or at the same inclination as the series of spindles A. The yarn is severed in any suitable manner, a 80 well known form of device 42, being conventionally illustrated.

The doffing operations as performed by our improved parts and the others of well known form as herein described, are as follows:—Assuming that the bobbins B have received the necessary quantity of yarn and that it is desired to remove them from the spindles A and substitute for them empty bobbins 33, the motions of the machine are 85 arrested and the arms of the fliers 1 moved into alinement with each other in the manner and for the purpose well known. The steadyng fingers or arms 23 are then moved into contact with the spindles A, while the 90 shaft 28 is rotated so as to project the pins 32 into the yarns on the bobbins B. The rail 8 supporting the lower ends of the spindles A is then lowered as is also the lifter plate 12, so as to both be clear of the lower 95 ends of the spindles, after which, the rail 2 is carried or moved into the position indicated by Fig. 2, by the rotation of the shaft 20, thus carrying with it the parts supported by the quadrants 18: hence the full bobbins 100 B will still be supported upon their spindles by the pins 32. The shaft 28 is now rotated in the opposite direction so as to withdraw said pins 32 from the yarns on the bobbins B, these latter then being allowed to fall 105 upon the pegs 34, which will be in the position at this time as indicated by Fig. 1.

The racks 38 are then moved by the shaft 40 so as to carry the two series of pegs 34, 35, into the positions indicated by Fig. 2, 110 wherein the pegs 35 are in alinement with said spindles A, and the pegs 34 moved away therefrom. The racks 26 are then lowered to a suitable position where by advancing the racks 30 and rotating the shaft 30^a the pins 32 may lay hold of the threads and move them to the proper sides of said spindles A, after which, said racks are slightly lowered and said pins 32 passed beneath the flanges of the bobbins 33, so that by raising 115 the racks 26 by the rotations of the shaft 24^a said empty bobbins are raised to an appropriate position over the spindles A when the rail 2 is again oscillated to bring the spindles into the positions indicated by Fig. 120 130

1. The lifter plate 12 and spindle rail 8 are then raised to their normal positions and the thread severed by any of the well known forms of thread cutting devices, conventionally illustrated at 42. The steady pins or arms 23 and pins 32 are returned to their normal positions and the bobbins 33 allowed to fall on to the lifter plate 12 in contact with which they are subjected to 10 a certain amount of drag and to the action of the device for imparting a drag to their side parts as hereinbefore described. A few turns are then given to the spindles after which the threads are severed in manner 15 well known. The spinning operations may then be recommenced.

From the foregoing description it will be seen that the performing of the doffing operations is considerably facilitated by having 20 supported from the parts which carry the spindles the means for holding and releasing the full bobbins, for supporting and moving the empty bobbins, and for moving or guiding the threads.

25 Such being the nature and object of our said invention what we claim is:—

1. A doffing apparatus for spinning machines comprising a frame, a supporting member pivotally mounted in said frame, a 30 series of spindles carried by and movable with said supporting member, pivoted bobbin engaging members, one for each spindle, said bobbin engaging members being carried by said pivoted supporting member, and means also carried by said pivoted supporting member for moving the bobbin engaging members longitudinally of the spindle.

2. A doffing apparatus for spinning machines comprising pivoted supporting members, spindles attached to and movable with the respective supporting members, pivoted bobbin-engaging members, one for each spindle, and means carried by said supporting 45 members for moving said bobbin-engaging members longitudinally of the spindles.

3. A doffing apparatus for spinning machines comprising a frame, a supporting member pivotally mounted in said frame, a 50 series of spindles carried by and movable with said supporting member, pivoted bobbin engaging members, one for each spindle, said bobbin engaging members being carried by said pivoted supporting member, means also carried by said pivoted supporting member for moving the bobbin engaging members longitudinally of the spindle, and means for moving the bobbin engaging members transversely of the spindle.

60 4. A doffing apparatus for spinning machines comprising a series of spindles, pivoted supporting members to which said spindles are rigidly attached, pivoted bobbin engaging members, one for each spindle, 65 means for moving said bobbin engaging

members longitudinally of the spindles, and means for oscillating said supporting members.

5. In doffing apparatus for spinning and like machines, a series of spindles, means 70 for rotating said spindles, hinged bearings supporting said spindles, brackets mounted on said hinged bearings, means for oscillating said brackets and spindles, bearings mounted on said brackets, movable racks extending through and guarded by said brackets, means for moving said rods through said brackets, brackets carried by said racks, bars sliding through said brackets, means for traversing said bars, and bobbin and 75 thread holding and guiding devices carried by said bars.

6. In doffing apparatus for spinning and like machines, a series of spindles, means 80 for rotating same, hinged bearings for said spindles, toothed quadrants carried by said hinged bearings, other quadrants gearing with said quadrants, means for oscillating same, bearings carried by said first-named quadrants, racks sliding through said bearings, means for traversing said racks, bearings carried by said sliding racks, racks slideable through said bearings, means for traversing said racks, and devices carried by said racks for moving and supporting the full 85 and empty bobbins and for guiding or moving the threads.

7. In doffing apparatus for spinning and like machines, a series of spindles, means 90 for rotating same, hinged bearings for said spindles, supports connected to said hinged bearings and provided with brackets, a shaft carried by said brackets, spindle steady devices mounted on said shaft, means for moving and supporting the bobbins and for 100 moving and guiding the threads, devices for sliding said bobbin moving and supporting device, and means for oscillating the said supports.

8. In doffing apparatus for spinning and like machines, a series of spindles, supports for same, brackets carried by said supports, hinged bearings for said spindles and brackets, spindle steady devices carried by said supports, means for oscillating same, bearings carried by said brackets, racks slideable through said brackets in paths approximately parallel with the spindles, bearings carried by said racks, racks sliding through said bearings in a direction approximately 110 at right angles to the spindles, means for moving said racks, a shaft carried by said racks and a series of plates carried by said racks and having extending pins, and means for oscillating said shaft.

9. In doffing apparatus for spinning and like machines, a series of spindles, means for rotating same, hinged bearings for same, brackets supported from said hinged bearings, means for oscillating said brackets, 115 120 125 130

spindle steadyng devices carried by said brackets, racks carried by said brackets, bearings carried by said racks, racks taking through said bearings, means for traversing said racks at right angles to their supporting racks, a rod carried by said racks and provided with extending pins for operating in connection with the full and empty bobbins, and pegs for the reception of said full and empty bobbins.

10. In doffing apparatus for spinning and like machines, a series of spindles, hinged bearings for said spindles, brackets mounted on said bearings, racks carried by said brackets, spindle steadiers carried by said brackets, bearings carried by said brackets, racks extending through said bearings, bobbin and thread moving devices carried by said racks, means for moving all these parts

15 simultaneously, means for moving said bobbin and thread operating devices separately, two series of pegs for receiving the full and empty bobbins, means for moving same, a spindle rail for steadyng the lower ends 20 of the spindles, and means for moving same.

25 11. In doffing apparatus for spinning and like machines, a series of spindles, and fliers, bearings for the upper ends of said spindles

a rail having bearings for the lower ends of said spindles, means for moving said rail, a thread severing device, devices for receiving the full and empty bobbins, a rail for supporting the upper ends of the spindles, means for tilting said rail, brackets carried by said rail, spindle steadyng devices, and 35 bobbin and thread moving devices carried by said rail, in combination.

12. In doffing apparatus for spinning and like machines, a series of spindles and fliers, means for rotating same, hinged bearings 40 for supporting same at their upper ends, a movable rail for steadyng same at their lower ends, a lifter plate traversed over said spindles, thread severing devices carried by said lifter plate, two series of pegs for 45 receiving the full and empty bobbins, means for supporting and moving said pegs, brackets carried by the spindles' upper supports, thread guiding or moving and bobbin supporting devices carried by said brackets, and means for oscillating said brackets and spindles simultaneously, in combination.

In testimony whereof we have signed our names to this specification.

ALFRED STELL.
JOHN STELL.
